Galph Burch

Attorney

UNITED STATES PATENT OFFICE.

FREDERIC W. PARKHILL, OF ARKANSAS CITY, KANSAS.

GOLF TEE.

Application filed September 12, 1924. Serial No. 737,271.

To all whom it may concern:

Be it known that I, FREDERIC W. PARKHILL, citizen of the United States, residing at Arkansas City, in the county of Cowley and State of Kansas, have invented certain new and useful Improvements in Golf Tees, of which the following is a specification.

My invention relates to improvements in golf tees and more particularly to a portable tee which may be conveniently carried by golf players, to use as a support for the golf ball when driving off.

It is an object of the invention to provide a tee formed from a single piece of material having a relative small head to support the ball, the sides of which form a contiguous part of the body.

A further object of the invention is to provide a portable tee having an anchor connected therewith which will serve as a resistance to the tee when in flight, so it will not travel far.

Another object of the invention is to provide an article of the above mentioned character which is simple and durable in construction, reliable and efficient in use, and inexpensive to manufacture.

Other objects and advantages of the invention will be apparent during the course 30 of the following description.

In the accompanying drawing, forming a part of this specification and in which like numerals are employed to designate like parts throughout the same,

Fig. 1, is a perspective view of the device in use,

Fig. 2, is a longitudinal sectional view of the tee,

Fig. 3, is a cross sectional view of the same, and,

Fig. 4, is a perspective view of the anchor plate.

In the drawing, wherein for the purpose of illustration I have shown a preferred embodiment of my invention, the body of the tee 5 is formed from a single piece of material, preferably wood, which is gradually tapered from a point adjacent its upper end, towards its lower end to define a sharp point 6, to facilitate the placing of the tee in the ground. The sides of the upper end of the body extend straight from and contiguous with the sides of the tapered portion, providing a relative small head 7 having its top surface dished or concaved, as

at 8, to provide a seat for the golf ball 9.

As more clearly shown in Fig. 2, the curvature of the ball is less than the curvature of the recess 8, so the ball merely rests on the peripheral edge of the recess and does not contact with the center. A groove 10 extends circumferentially around the body at the point where it starts to taper, to indicate the depth at which the tee should be placed in the ground.

To limit the flight of the tee through the air should it be struck by the golf club, an anchor 11 is connected to the tee by a length of cord or wire 12. The anchor is preferably formed from a flat rectangular piece of metal 13 having one of its ends slightly reduced, as at 14, and bent upon itself, as at 15, having a central aperture 16 at the bend to receive one end of the cord 12 which is knotted and securely held in place by the bent end. The opposite end of the cord is inserted in an opening 17 in the side of the tee adjacent the upper end and secured in place by glue and a wedge 18.

In use, the tee may be conveniently carried about the golf course and readily inserted in the ground to support the ball when driving off. It will be observed, that owing to the relative smallness of the seat upon which the ball rests the radius of the ball will be a sufficient distance from the edge of the seat to prevent any English, side lash, or come back to the ball when struck by the club. The head of the tee is free from flanges and does not extend beyond the sides of the body, so that the head will not be broken from the body should it be struck by the club. If in driving off the tee is carried into the air, the anchoring plate will flutter, affording sufficient resistance to the flight of the tee, so it will not travel far.

It is to be understood that the form of my invention herewith shown and described is to be taken as a preferred example of the same and that certain changes in the shape, size and arrangement of parts may be resorted to without departing from the spirit of the invention or the scope of the subjoined claims.

Having thus described my invention I claim:

1. A golf tee formed from a single piece of material comprising a tapered shank having a straight head extending vertically from said shank, said head having its upper surface concaved to provide a seat for

- the golf ball, an anchor plate, and flexible means connecting said plate with said shank.
2. A golf tee formed from a single piece of material comprising a tapered shank having a straight head integral with said shank, said head being concaved to provide a seat for the golf ball, an anchor plate having a reduced end bent upon itself and having a central aperture at its bend and a flexible member having one of its ends inserted in said aperture and secured in place by the bent end, the opposite end of the member being secured to said shank.
3. A golf tee formed from a single piece of material comprising a head having a tapered shank extending axially therefrom,
- said head having its upper surface concaved to provide a seat for the ball, an anchor plate and flexible means connecting said plate with said shank.
4. A golf tee formed from a single piece of material comprising a body tapered for the greater portion of its length to provide a shank, the upper end of said body terminating in a cylindrical head, the diameter of said head corresponding with the greatest diameter of the tapered portion, said head having its upper surface concaved.

In testimony whereof I affix my signature.

FREDERIC W. PARKHILL.
